CATHODE RAY TUBE

Ernst Ruska, Berlin-Zehlendorf, Germany, assignor to the firm Fernseh Aktiengesellschaft, Zehlendorf, near Berlin, Germany

Application September 16, 1936, Serial No. 101,172
In Germany September 24, 1935

2 Claims. (Cl. 250—141)

The present invention relates to an especially simple method for fastening electrode systems in electron tubes, especially those involving secondary emission, and particularly multiplier tubes and electron ray tubes, for example those intended for image scanning and image composing as well as oscilloscope work.

In the production of Braun tubes it is particularly desirable that the electrode system be positioned against the neck of the tube in as simple a manner as possible and held rigid therein before the glass foot is fused together with the neck of the tube.

In accordance with the invention spread rings are provided at one or more places of the portions of the tube destined to receive the electrode system and to which rings the individual electrodes or an entire electrode system are fastened. The spread rings are preferably in the form of short, slotted, thin-walled cylinders. In order to hold any of the electrodes of the electrode system the cylinder is provided with a cross yoke which is fastened thereto at right angles e. g. by welding or riveting, or it may be bent out at right angles to the ray and tube axis as a portion of the spread ring. This cross yoke then serves for retaining the electrodes. However, it is also preferable to form the cross yoke itself as an electrode which is then connected with the spread ring.

The width of these bent-out lugs must be small at the bending point if the spread ring at this point is not to suffer in its resilient qualities. In order to impart sufficient stiffness to the electrodes as compared with the spread ring, two lugs may be bent out at points on the spread ring at points separated about 180° apart, and preferably in such fashion that the one lug aids in supporting the other in both axial directions. For this purpose the second lug is formed as a fork at its ends so as to maintain a free movability of both lugs with respect to each other in a plane perpendicular to the tube axis (spread ring plane). However one lug will suffice for fastening the anode diaphragm in a manner stiff enough to permit bending if it is supplementarily supported against the spread ring by means of a small support member.

Owing to the baking process to which the tube is subjected, the material used for the spread rings should preferably be a resilient material possessing great resistance to heat and softening, such as chromium-nickel, nickel-beryllium alloys, in addition, in most cases non-magnetic material must be used in making the spread rings. For

this purpose the alloy known commercially as "Contrazidberyllium" is particularly suited.

In cases where a conducting, high or low ohmic interior coating is disposed on the wall of the tube, the spread ring also simultaneously serves the function of making contact between the coating and the electrode which latter is at the same potential. Such contact is a particularly positive one inasmuch as large surfaces are brought into contact with adequate pressure. Scraping or scratching of the very sensitive inner wall of the tube (producing danger of cracking in the case of glass tubes) may readily be obviated by introducing the spread ring in squeezed-together condition into the neck of the tube by means of special tools and then first allowing it to expand when correctly positioned so that it fits against the wall of the tube. For this purpose both ends of the ring may be provided with inwardly bent lugs by means of which the ring may be squeezed together from its inside so as to be able readily to insert or remove it. For this purpose obviously a sufficient width of slit must be available. The resilient force of the spread ring may be such, without endangering the material of the tube (glass, ceramic material), that a very positive and rigid positioning of the electrodes is effected. In other cases, in order to attain better adhesion of the spread ring to the inner wall of the tube, the wall thereof or the material of the spread ring may be roughened or provided with flutings running in the direction of the tube axis. The curvature of the spread ring is preferably less in the center than at the two ends, and for the reason that the terminal curvature may be adapted to the width of the tube so that when finally positioned it becomes uniformly pressed against the neck.

In case one spread ring is destined to carry an entire electrode system, the said system prior to insertion may be mounted on a glass socket provided with lead-ins, e. g. a press-foot, and then inserted into the neck of the tube in a mechanically rigid manner by means of special tools. The melting together of the neck of the tube and the glass foot may then be effected in a simple manner while insuring the exact coaxial positioning of the system with respect to the tube.

In the drawing:

Fig. 1 shows a spread ring according to the invention.

Fig. 2 is a top view of Fig. 1.

Fig. 3 is a spread ring which serves for holding an electrode system.

Fig. 4 is an arrangement of a number of spread rings within the tube portion provided therefor.

In Fig. 1, 1 indicates the wall of the tube against which the spread ring 2 is pressed. The cross yoke fastened to the spread ring consists of two oppositely located lugs 3, and 4, 5. Lugs 4 and 5 are preferably so formed that they constitute a fork which is adapted to support the lug 3 in both axial directions. The lugs 4 and 5 may be omitted 10 in case they appear to be unnecessary. An anode ring and diaphragm 6 is fastened to the cross yoke, by an insulating ring 7 threadably engaging over said diaphragm ring, said rings being both provided with threads and serving for holding the 15 accelerating system. The two ends of the spread ring 2 which form the slit are bent over to form lugs 8 as shown in Fig. 2 so that when the spread ring is squeezed together a good grip will be provided for the tool used.

Fig. 3 shows by way of example the use of the spread ring of the invention for fastening an electrode system as used in a Braun tube intended for television reception purposes. An anode diaphragm 6 is positively centered upon a cross yoke 3, preferably together with a Wehnelt cylinder 9, the said yoke being, for example, fastened by spot welding to the center of the spread ring 2 and perpendicular thereto. By means of spread ring 2 the entire system may thus be rigidly anchored 20 into the tube portion 1 without using any special device thereon. However, as shown in Fig. 3 the anode diaphragm 6 may be held in a hole in the cross yoke by means of an insulating threaded ring 7. The control electrode 9 of the 25 cathode which is fastened to the press foot, is screwed into the insulating threaded ring 7, and centered thereby with respect to the anode system, whereupon the press foot is fused together with the neck of the tube. In this embodiment the spread ring 2 effects contact between the coating 30 12 and the anode diaphragm 6.

Fig. 4 shows the arrangement of a number of spread rings 2, 2', 2'' which serve for receiving individual electrodes, e. g. the control electrode 9, the anode diaphragm 6 with the anode tube 10, and the anode disk 11, respectively. During the fastening of the anode diaphragm 6 together with the anode tube 10 to the spread ring 2' the procedure may be such that the anode tube 10 is 35 centered by means of three bent over lugs not shown with respect to a hole in the cross yoke 3' through which the anode diaphragm and tube 6 provided with external threads and flange is inserted from the screen side. The anode diaphragm 6 is then, together with the lugs of the anode tube 10, drawn up tight by means of a threaded sleeve (not shown) to the cross yoke 3'. In the embodiment shown in the drawing the aforesaid three parts are shown connected together by spot welding. In this case it is prefer-

able to stiffen the cross yoke 3' by means of a support arm 13. By using a number of spread rings it is easy, when mounting the electrode system, to adjust the individual electrodes with respect to each other.

The invention is obviously not limited to the foregoing examples. For example a plurality of spread ring electrodes may be inserted at various portions of the tube. This has the particular advantage that various types of tubes which differ mainly through the axial separation of their electrodes may be produced by using the same individual electrodes except that they are inserted with different degrees of separation.

In lieu of one spread ring for fastening electrodes which extend lengthwise in the direction 15 of the tube axis, as for example the anode tube 10, two or more small or wire-shaped spread rings 20 may also be used and disposed at both ends of the electrodes or distributed along the length of the entire electrode.

It has been found to be preferable, when dealing with a tubular electrode, to position a portion 25 of the electrode by means of a spread ring which is not applied to the wall of the tube but rather to the inner side of the electrode.

I claim:

1. In a cathode ray tube, electrode positioning means comprising a split expandable metallic ring adapted to fit within and press against said tube, the ends of said ring adjacent the split therein being bent inwardly, oppositely disposed main lugs formed integrally with said ring and extending inwardly therefrom across and normal to the axis of said tube, an auxiliary lug formed upon and parallel to one of said main lugs, said auxiliary lug and its main lug being adapted to fit around and firmly position the oppositely disposed main lug against movement parallel to the axis of said tube, and means disposed through said main lugs 40 adapted to receive an electrode to be supported and fixedly attached thereto.

2. In a cathode ray tube, electrode positioning means comprising a split, expandable, metallic ring adapted to fit within and press against said tube, the ends of said ring adjacent the split therein being bent inwardly, oppositely disposed main lugs formed integrally with said ring and extending inwardly therefrom across and normal to the axis of said tube, an auxiliary lug formed upon and parallel to one of said main lugs, said auxiliary lug and its main lug being adapted to fit around and firmly position the oppositely disposed main lug against movement parallel to the axis of said tube, means disposed through said main lugs 50 adapted to receive an electrode to be supported and fixedly attached thereto, an insulating member attached to said electrode, and an additional electrode supported by said insulating member.

ERNST RUSKA.
